UNITED STATES PATENT OFFICE.

JOHN F. MCNEIL, OF PHOENIX, ARIZONA.

PERFUME-VENDING MACHINE.

1,222,224.

Specification of Letters Patent. Patented Apr. 10, 1917.

Application filed February 1, 1916. Serial No. 75,584.

To all whom it may concern:

Be it known that I, JOHN F. MCNEIL, a citizen of the United States, residing at Phoenix, in the county of Maricopa and 5 State of Arizona, have invented certain new and useful Improvements in Perfume-Vending Machines, of which the following is a specification.

My present invention relates to certain 10 new and useful improvements in perfume vending apparatus and as its general object, it contemplates the provision of a novel device of this nature that may be constructed so as to be coin controlled and which may be 15 easily and quickly operated so as to spray the perfume onto the handkerchief or the lapel of the coat of the wearer.

A further object of my invention is to provide a device of the type in question that is 20 extremely simple in construction, strong and durable, and highly practical from both the standpoint of the manufacturer and the standpoint of the user; and which, it is believed, may be manufactured at a comparatively 25 low cost.

Various other objects and advantages will become apparent during the continuance of the following description.

These objects are accomplished by such 30 means as are shown in their preferred form in the accompanying drawings, described in the following specifications and then more specifically pointed out in the appended claims.

35 In the accompanying drawings wherein like characters designate like parts throughout the several views:—

Figure 1 is a view in front elevation showing my invention as in its preferred embodiment;

Fig. 2 is a view in longitudinal section showing the interior mechanism of the device in elevation;

Fig. 3 is a view in cross section;

45 Fig. 4 is a sectional view taken on line 4—4 of Fig. 1; and

Fig. 5 is a view in perspective of a novel form of container support.

In reducing my invention to practice, I 50 first provide a suitable base 10, upon which may be mounted a suitable housing or casing 11 of any desired form. The housing 11 is in turn provided with a door portion 12, hinged as at 13, while the latter carries a 55 transparent plate 14, through which the directions for operating the device may be

viewed. The door portion 12 carries a suitable locking device 15, whose bolt member 16 may be received into a suitable aperture in one of the side walls of the housing, while 60 any desired form of key or other operating member may be employed for the purpose of actuating the lock. The housing 11, as well as the door 12 thereof, may be formed of any desired material, however, it is pointed out that metal is preferable.

To the upper wall of the housing, I affix a coin receiver 17 which communicates with the interior of the same, while a track 18 may be affixed to the rear wall of the housing, at an incline in proximity to the receiver 17 to receive the coin upon its insertion into the housing. A guide plate 19 may also be arranged in conjunction with the track 18 and secured as at 20 so as to provide for the 75 proper guiding of the coin such as will subsequently appear.

In order to accommodate the body of the perfume atomizer, I provide the housing 11 with a suitable holder, as designated in its 80 entirety by the numeral 21 (see Fig. 2), the spout or disk portion 23 of the atomizer being positioned in a delivery spout or chute 24, that is associated with the door of the housing, as shown in Fig. 3. The air inlet 85 tube of the atomizer, which is designated by the numeral 25 is provided at one end with an enlarged head 26, as clearly shown in Fig. 2, while the head portion movably accommodates the socket 27, of a flexible tube 90 28. Any desirable form of air bulb may be employed; however, in the drawings, I have shown one of conventional form that consists of a leather body 29, merging at one end into an extension 30, whose reduced threaded 95 portion 31 may be received by the flexible tube 28, in the manner shown. Consequently, upon compression of the bulb 29, a portion of the contents of the atomizer will be ejected through the spout 23, as is obvious. 100

With a view of providing means for adequately supporting the bulb 29 of the atomizer and for the secure retainment of the same during its compression and expansion, I equip one of the side walls of the housing 105 with a carrying bracket 32, secured as at 33, the bracket in turn carrying a concaved receiving platform 34 to receive the bulb in the manner shown. In order to further add to the rigidity of the platform 34, I may utilize 110 a brace arm 35 whose upper end may be attached to the under face of the platform

while its lower end may be connected with the bracket 32, as shown.

I further provide an actuating lever 36, one end thereof being pivotally connected as at 37 to a bearing, while its other end projects through a slot 39 in the other side wall of the housing. At its free end, the lever 36 carries a hand grip 40 whereby it may be conveniently operated while it is arcuately curved as at 41 intermediate its ends and provided with an adjacent plate 42 to act on the bulb 29 of the atomizer, in the manner shown. Consequently, it will be seen that upon applying a downward pressure to the hand grip 40 of the lever, the adjacent plate 42 will be made to bear on the bulb 29, such as will cause the compression thereof and the consequent actuation of the atomizer in the usual manner. Upon release of the hand grip, the bulb will automatically expand to its initial position, thereby raising the lever 36 and the hand grip to the position shown in Fig. 3.

The rear wall of the housing further carries a coin actuated lever 43, the supporting stud 44 thereof receiving the slotted portion 45 of the lever, as clearly shown in Fig. 2. Adjacent its upward end, the lever is provided with an abutment 46 that is designed to normally lie adjacent the lower end of the track 18 and the guide plate 19, while adjacent its lower end, the lever carries a lateral guiding extension 47 upon which the coin is received subsequent to its engagement with the abutment 46. In other words, when the coin is deposited upon the track 18 by way of the receiver 17, it will move by action of gravity into engagement with the abutment 46 of lever 43, such as will cause the dropping of the lever into the position shown in dotted lines in Fig. 2. Upon the rocking of the lever into this position, the coin will drop past the abutment 46 and thence be engaged with the extension 47, wherefrom it will fall directly into the body of the housing.

I further provide one side wall of the housing 11 with a bar 48 secured as at 49, the same being provided with rack teeth 50 throughout a portion of its longitudinal extent and further provided with a guiding plate 51. The lever 36 is provided with a movable pawl 52 whose collar portion 53 is received thereon in the manner shown, 55 while the collar in turn carries an oppositely projecting extension 54 to be engaged at certain times with the upper end of the lever 43. As will be noted upon reference to Fig. 4, the pawl 52 is arcuately curved so that upon movement of the actuating lever into a position shown in Fig. 2, the pawl will be automatically shifted to assume the position shown in full lines in Fig. 4. When in the position shown in Fig. 4, the extension 54 of the collar 53 will be out of verti-

cal alinement with the lever 43, whereby upon downward movement of the free end of the actuating lever, the pawl 52 will be engaged with the upper one of the teeth 50 of the bar 48, thus preventing further movement of the said lever. On the other hand, should the lever 43 be in the position shown in dotted lines in Fig. 2 upon downward movement of the free end of the actuating lever, the extension 54 will ride upon the upper end of the lever 43 thereby shifting the pawl 52 so as to draw the same out of an engaging position with the teeth 50 and as a consequence permitting the free depression of the actuating lever and the consequent actuation of the atomizer.

In Fig. 5, I have shown a novel form of holder 21 that is designed to be used for the purpose of accommodating the body 22 of the atomizer. This holder consists preferably of a single strand of wire bent first at a point 55 to form parallel arms 56, the said arms being bent at their lower ends to form angular gripping jaws 57. At their free ends, the jaws 57 are again bent to form depending portions 58, while the strand is further bent adjacent the depending portions 58 to form supporting arms 59, which finally terminate in fingers 60, that are suitably secured to the gripping jaws 57 adjacent their juncture with the arms 56, in the manner shown. When in an opposite position, such as shown in Fig. 2, the engaging jaws 57 of the holder fit snugly about the intermediate portion of the body of the atomizer, while the supporting portions 59 extend therebeneath and securely retain the same against downward movement. By reason of the flexibility of the holder, the same may be utilized to accommodate bodies of varying heights and diameters, whereby, it will be understood I am not restricted to any specific type of atomizer to be used.

The operation of my invention is substantially as follows:—

Upon insertion of a coin of predetermined denomination in the receiver 17, the same will drop onto the trackway 18 and hence move, by action of gravity, into engagement with the abutment 46 of the lever 43. Upon its engagement with the abutment 46, the lever 43 will be shifted into the position shown in dotted lines in Fig. 2, thereby bringing its upper end into alinement with the extension 54 of the collar 53 in the manner shown. Upon depression of the free end of the actuating lever, the free end of the extension 54 will ride upon the upper end of the lever 43 so as to shift the pawl 52 into the position shown in dotted lines in Fig. 4, whereby the same will be brought out of engagement or out of an engaging position with the teeth 50 of the bar 48. Consequently, it will be noted that the lever 36 may be depressed to the desired extent, such

as will cause the compression of the bulb 29 and the proper actuation of the atomizer. The coin which is initially engaged with the abutment 46 will fall onto the extension 47 of the lever 43 and upon the shifting of the lever to its initial position will fall into the housing 11.

From the foregoing, it is believed that the advantages and novel features of my invention will be readily understood and, therefore, further detail description is deemed unnecessary.

In reducing my invention to practice I find that the form referred to herein is the most practical and preferred embodiment, and is the most efficient, but realizing that certain conditions will necessarily vary in concurrence with the adoption of my device, I desire to emphasize the fact that various minor changes in the details of construction and in the proportion of parts may be resorted to when required without sacrificing any of the advantages of my invention as defined in the appended claims.

Having thus fully described my invention, what I claim as new and desire to secure by Letters Patent is:—

1. In a vending machine of the character described, a housing, a holder arranged in said housing, a perfume atomizer to be carried by said holder, the spout of said atomizer communicating exteriorly of said housing, a pneumatic bulb associated with said atomizer, means to support said bulb, an actuating lever pivoted at one end in said housing, the free end of said actuating lever projecting exteriorly of said housing, an engaging plate on said actuating lever to bear against said bulb whereby the same may be compressed upon the depression of the free end of the actuating lever, a rack bar fixed to said housing, means carried by said actuating lever to normally engage with said rack bar to prevent actuation of said lever, and means to become operative upon the positioning of a coin in said housing to shift said last mentioned means upon actuation of said lever whereby the lever may be moved into a position to compress said bulb, as and for the purpose specified.

2. In a vending machine of the character described, a housing, a holder detachably arranged in said housing, a perfume atomizer carried by said holder, the spout of said atomizer communicating exteriorly of said housing, a pneumatic bulb associated with said atomizer, means to support said bulb, an actuating lever pivoted at one end in said housing, the free end of said actuating lever projecting exteriorly of said housing, an engaging plate on said actuating lever to normally bear against said bulb whereby the latter may be compressed upon the depression of said actuating lever, a rack bar fixed to said housing, a collar movably mounted

on said actuating lever, a pawl projecting from one side of said collar to normally engage with said rack bar whereby movement of said actuating lever will be prevented, the extension on said collar extending oppositely to said pawl, a lever pivotally mounted in said housing, an abutment on said lever, a coin chute associated with said housing, said abutment normally lying at the end of said coin chute, whereby upon the positioning of a coin in said chute, said abutment will be acted upon to shift said last mentioned lever into a position whereby said extension will ride upon the upper end of the same during the depression of said actuating lever thereby drawing said pawl out of engagement with the rack teeth of said rack bar and permitting said actuating lever to be moved into position to compress said bulb, as and for the purpose specified.

3. In a vending machine of the character described a housing, an atomizer formed in said housing and including a pneumatic bulb, an actuating lever pivoted at one end in said housing and having its free end projecting exteriorly of said housing, said actuating lever bearing against said bulb to compress the bulb upon depression of the free end of the actuating lever, a rack bar affixed to said housing, means carried by said actuating lever to normally engage said rack bar and prevent actuation of said lever, and means to become operative upon the positioning of a coin in said housing to shift said last mentioned means upon actuation of said lever whereby the lever may be moved to a position to compress the bulb.

4. In a vending machine of the character described a housing, a bulb in said housing, an actuating lever pivoted at one end in said housing with its free end projecting exteriorly of the housing, the lever bearing against said bulb for compressing the bulb upon depression of said actuating lever, a rack bar in said housing, a pawl mounted upon said actuating lever to normally engage the rack bar and prevent downward movement of the lever, said pawl being provided with a handle extension, a coin chute associated with said housing, a lever pivotally mounted in said housing and having an abutment normally lying at the end of the coin chute whereby a coin passing through said chute will engage the abutment to shift the last mentioned lever into position whereby the handle extension of the pawl will ride upon the upper end portion of the last mentioned lever during compression of the actuating lever and move the pawl out of engagement with the rack.

5. In a vending machine a housing, a pneumatic bulb mounted in said housing, a rack bar in said housing, a stop lever mov-

ably mounted in the housing, an actuating element movably mounted in the housing for engagement with the bulb to compress the bulb upon movement of the actuating element in one direction, the stop lever normally extending adjacent a coin chute for engagement by a coin to move the stop out of its normal position, and a pawl movably connected with the actuating element to engage the rack and prevent movement of the lever to an operative position with respect to the bulb, the stop lever when swung out of its normal position engaging the pawl to swing the same out of engagement with the rack and permit the actuating element to be moved into operative engagement with the bulb.

6. A coin controlled vending machine including a housing, an actuating lever movably mounted in the housing and having its free end portion extending beyond the housing, a rack in the housing adjacent the

lever, a pawl loosely mounted upon the lever and normally extending to engage the rack bar and prevent movement of the lever to an operative position, a coin chute, and a cam element movably mounted in the housing in operative relation to the coin chute and pawl and normally positioned out of position for engagement with the pawl and in position for engagement by a coin passing through the coin chute, the cam element when engaged by a coin moving into the path of movement of the pawl for engaging the pawl and swinging the pawl out of position for engagement with the rack bar when the actuating lever is moved toward an operative position.

In testimony whereof I affix my signature in presence of two witnesses.

JOHN F. MCNEIL.
